PLASTER APPLICATOR

Alan C. Gott, P.O. Box 164, Arlington, Mass.

Filed Oct. 27, 1964, Ser. No. 82,331

Term of patent 14 years

(Cl. D51—1)

FIG. 1 is a side elevational view of the plaster applicator;

FIG. 2 is a side elevational view opposite to that of FIG. 1 of the plaster applicator;

FIG. 3 is a top plan view of the plaster applicator; and

FIG. 4 is an end elevational view thereof.

The handle has been shortened in FIGS. 2 and 4, for ease of illustration.

I claim:

The ornamental design for a plaster applicator, as shown and described.
